UNITED STATES PATENT OFFICE.

CHRISTOPHER C. BOYKIN, OF NORFOLK, VIRGINIA.

WINDOW-SCREEN.

1,117,941.

Specification of Letters Patent. Patented Nov. 17, 1914.

Application filed September 25, 1913. Serial No. 791,822.

To all whom it may concern:

Be it known that I, CHRISTOPHER C. BOYKIN, a citizen of the United States, residing at Norfolk, in the county of Norfolk and State of Virginia, have invented new and useful Improvements in Window-Screens, of which the following is a specification.

This invention relates to improvements in window screens, and it has for its objects primarily to provide a screen which can be placed on the outside of the window in such manner as to avoid interference with the raising and lowering of the lower window sash and will avoid interference with the fastenings of outside blinds or shutters when such are used, enabling the blinds or shutters to be opened and closed conveniently, which can be readily accommodated to window openings of different widths and heights and will maintain a tight closure to exclude flies and other insects, and which can be manufactured and installed readily and cheaply.

To these and other ends, the invention consists in certain improvements, and combinations and arrangements of parts, all as will be hereinafter more fully described, the novel features being pointed out particularly in the claims at the end of the specification.

In the accompanying drawing: Figure 1 is a perspective view of a window showing a screen constructed in accordance with the present invention applied thereto; Fig. 2 represents a vertical section through the window showing the position of the screen with respect thereto; Fig. 3 represents a horizontal section on the line 3—3 of Fig. 2; Figs. 4 and 5 are detail perspective views showing the construction of the upper and lower rails of the screen; Fig. 6 is a detail view of a device for temporarily deflecting the upper portion of the screen to provide an exit for flies; Fig. 7 is a detail view of the catches which hold the lower ends of the guides in proper position.

Similar parts are designated by the same reference characters in the several views.

Window screens embodying the present invention are applicable generally to windows of different styles, the screen in the present instance being shown in connection with a window of the usual construction. It will be understood, however, that the invention is not restricted in this regard and also that modifications and changes may be made, all of which will be included within the scope

of the claims at the end of this specification.

In the presence instance, 1 designates the window frame having a sill 2, and 3 designates the upper sash which is shown in its usual elevated position and is fitted in the grooves or channels 4 formed in the opposite sides of the window frame. The screen embodies a section of screen cloth 5 which is preferably metallic or composed of woven wire and corresponds substantially in dimensions to the size of the opening defined by the sides of the window frame, the sill, and the lower rail of the upper sash. The lower edge of the screen cloth is attached to the lower rail 6 of the screen, which may be of wood, by a strip 7, the latter being composed preferably of sheet metal having the lower edge of the screen cloth secured thereto by folding the strip, the strip being secured by screws or other suitable means to the lower rail 6 of the screen. The upper edge of the screen cloth is secured to the upper rail 8 of the screen, this rail being composed preferably of sheet metal which is doubled to form a groove which is open at the bottom, and the upper edge of the screen cloth is folded or doubled so as to fit into this groove in the upper rail, it being secured therein by a bar 9 which is inserted into the folded portion of the screen cloth and introduced into the groove in the rail 8. One edge of the upper rail is preferably folded and turned outwardly to form a stiffening flange 10 and the retaining bar 9 is preferably locked or held in position relatively to the upper rail 8 by a pair of tongues 11 which are formed by splitting the ends of this bar and folding such tongues against the rail 8 so as to lie above the flange 10, as shown in Fig. 4.

A pair of guides are provided at the opposite sides of the window frame to coöperate with the screen to guide the same and to also produce tight closures at these points to effectually exclude flies and other insects. In the present instance, a pair of such guides 12 are shown, these guides being similar in construction and being of angle form in cross section, the guides being fitted into the sash grooves or channels 4 with the outer flanges 13 lying against the bottoms of the grooves and the other flanges 14 of the guides being turned inwardly or toward one another, as shown in Fig. 3. The upper ends of these guides may be retained in po-

sition by fitting them between the lower corners of the upper sash and the respective walls of the groove while the lower ends of the guides are retained in position by catches 15, each having upstanding flanges formed with slots 16 to receive the inturned flanges 14 of the respective guides. The guides can be readily removed by lifting their lower ends from the slots 16 and then 10 withdrawing their upper ends by a downward movement. These guides are curved inwardly toward their lower ends, giving the guides a curved or convexed form, as shown in Figs. 1 and 2. This feature not 15 only brings the lower rail 6 of the screen inwardly to a point where it will not interfere with the catches 17 which fasten the outside blinds or shutters, but also insures contact between the guides and the side 20 edges of the screen cloth throughout the height of the screen, it being understood that these side edges of the screen are unattached or not provided with rails. In order to insure such contact between the 25 side edges of the screen and the guides, means is provided for maintaining the screen under tension. According to the present invention, a pair of tension springs 30 are provided, these springs being attached to the upper part of the window frame by the eyes 19 and are fastened at their lower ends to the upper rail 8 of the screen, these springs exerting a constant tension upon the screen and hence causing 35 the side edges thereof to lie in close contact with the inturned flanges 14 of the guides, the curved or convexed form of the guides insuring contact between them and the screen cloth throughout their extent. A 40 suitable catch is also provided to normally retain the screen in closed position in opposition to the lifting action of the springs 18. The catch shown in the present instance embodies an eye or staple 20 which 45 is secured to the window sill and a projection 21 which is secured to the lower rail 6 of the screen. The upper rail 8 of the screen is held in proper position by the projecting ends of the bar 9 which lie against 50 the inturned flanges 14 of the guides. The lower rail of the screen is also held in proper position by the guides 12. In the construction shown, means is provided for adjusting the width of the lower rail of the 55 screen to conform to the width of the window opening, a slide 22 being shown which is held in proper adjusted position on the rail 6 by a screw 23 secured in the rail and extending through a slot 24 in the slide. 60 The slide 22 forms a space between it and the strip 7 into which projects the inwardly extending flange 14 of the respective guide. These slides can be readily set at different 65 positions in the direction of the length of the lower rail 6 of the screen in order to

accommodate the width of the screen to the width of the window opening, and the upper rail of the screen can be readily cut to the proper length. The height of the screen can be adjusted readily by making a fold 70 of the proper length in the screen cloth at the point where the latter is secured to the upper rail. The opening provided between each slide 22 and the strip 7 for the guides 12 is sufficiently large to permit the lower rail 6 of the screen to have a limited rocking movement, this rocking movement of the lower rail of the screen serving to engage and disengage the catch composed of the eye 20 and the projection 21. When it 75 is desired to open or close the outside blinds or shutters, it is only necessary to rock the lower screen rail 6 to disengage the projection thereon from the eye, the springs 18 then operating to lift the screen a distance 80 sufficient to admit the hand to the blind fastenings, the screen, however, being normally retained in its lower closed position by the catch as described. If desired, a device 85 such as that shown in Figs. 2 and 6 may be 90 provided for temporarily deflecting the upper end of the screen outwardly to provide an exit for flies. This device as shown consists of a plate 25 which is pivoted at 26 to the under side of the upper sash 3, this 95 catch, when it occupies the position shown in Fig. 2, being disengaged from the screen, the upper rail of the screen then lying directly against the outer side of the lower rail of the upper sash 3, as shown in Fig. 2, and when turned into the position shown in Fig. 6, it will engage and force outwardly 100 the upper end of the screen, providing an exit between the upper end of the screen and the lower rail of the upper sash. 105

I claim as my invention:

1. In a window screen, the combination of a section of flexible screen cloth, a pair of longitudinally curved guides, and means for maintaining co-operative relation between 110 said guides and the side edges of the screen cloth to form tight closures.
2. In a window screen, the combination of a section of screen cloth, a pair of guides projecting inwardly beyond the side edges of 115 the screen cloth, and means for exerting tension on the screen cloth to maintain the same in close engagement with said guides.
3. In a window screen, the combination of a section of screen cloth, a pair of vertical 120 longitudinally curved guides, and tensioning means operative to maintain the side edges of the screen cloth in close engagement with said guides.
4. In a window screen, the combination of 125 a section of screen cloth, a pair of vertical longitudinally bowed guides, and springs operative to maintain the screen cloth under tension with the side edges thereof in close engagement with said bowed guides. 130

5. The combination of a section of flexible screen cloth having rigid rails attached to its upper and lower edges, vertical guides adapted to fit into a window frame and having flanges extending inwardly beyond the side edges of the screen cloth, tensioning means operative to maintain the side edges of the screen cloth in close engagement with the flanges of the guides, and a catch coöperative with said lower rail to normally retain the screen in closed position. 35
6. The combination of a window frame having channels in the sides thereof for an upper sash, a pair of guides fitted in said channels and bowed from the top of the window opening inwardly to the bottom of the window opening, a screen covering the window opening, and means for holding the screen in contact with said bowed guides. 40
7. The combination of a pair of guides adapted to be arranged at opposite sides of a window frame, a screen embodying upper and lower rails movable vertically on said guides, the lower rail being capable of a rocking movement on said guides, means operating to lift the screen, and a catch for normally holding the screen in lowered position, said catch being controlled by said rocking movement of the lower rail. 45
8. The combination of a pair of guides at opposite sides of a window frame, a screen having means for pressing it yieldably against said guides, and a device for deflecting the upper end of the screen relatively to said guides to afford an exit opening. 50
9. In a screen, the combination of a section of screen cloth and a rail adapted to be secured thereto embodying a member doubled to form a groove to receive a doubled edge of the screen cloth, a bar lying in the doubled portion of the screen cloth and locking the same in the groove of said member, and bendable tongues locking said bar in the groove of said member. 55
10. In a screen, the combination of a pair of guides, and a screen embodying a rail having slots slidably receiving said guides, the rail having a slide adjustable longitudinally thereon at one side of its respective slot and in a direction toward and from the respective guide to accommodate the screen to window openings of different widths. 60
- In testimony whereof I have hereunto set my hand in presence of two subscribing witnesses. 55
